UNITED STATES PATENT OFFICE

113,871

DESIGN FOR A GRILLE GUARD

Philip C. Marrera, Chicago, Ill.

Application July 26, 1938, Serial No. 78,752

Term of patent 7 years

To all whom it may concern:

Be it known that I, Philip C. Marrera, a citizen of the United States of America, residing at Chicago, county of Cook, and State of Illinois, have invented a new, original, and ornamental Design for a Grille Guard, of which the following is a specification, reference being had to the accompanying drawing, forming part thereof wherein:

I claim:

The ornamental design for a grille guard, as shown.

PHILIP C. MARRERA.
